UNITED STATES PATENT OFFICE.

EDWARD SCHREFFLER, OF KILLINGER, PENNSYLVANIA.

LAWN-MOWER.

SPECIFICATION forming part of Letters Patent No. 568,146, dated September 22, 1896.

Application filed March 10, 1896. Serial No. 582,645. (No model.)

To all whom it may concern:

Be it known that I, EDWARD SCHREFFLER, a citizen of the United States, residing at Killinger, in the county of Dauphin and State of Pennsylvania, have invented certain new and useful Improvements in Lawn-Mowers, of which the following is a specification, reference being had therein to the accompanying drawings.

10 The object of my invention is to produce a lawn-mower of simple and inexpensive construction adapted to cut grass of any height and close to fences, curbstones, or other obstructions without danger of damaging its parts. I attain this object by the construction illustrated in the accompanying drawings, in which—

Figure 1 is a perspective view of a mowing-machine constructed in accordance with my invention. Fig. 2 is a top view of the same.

In said drawings, A represents the frame, which is rectangular in form and is carried by the wheels B and B², which revolve upon stud-axles projecting from the sides a and a² of the frame. The wheel B² has secured to the inner side of its spokes a slightly-beveled cog-wheel C, to give motion to the balance of the mechanism. Said wheel B², being the driving-wheel, may have cleats projecting 30 from its periphery, as commonly used in various kinds of mowers.

The frame consists of the two side pieces a and a², both on the inner side of the carrying-wheels and alongside thereof, the front 35 35 or cutter bar a³, and the rear piece a⁴. Said parts a a² a³ a⁴ are preferably made integral. Attached to the inner side of the side piece a² and rear piece a⁴ there is a brace A² to provide bearings for a gear-wheel shaft and the 40 pitman-shaft used to operate the reciprocating knife employed with the machine.

The side piece a² is transversely slotted for the passage of a pinion D, that meshes with the cog-wheel C. Said pinion D is mounted 45 upon a shaft d, that is along the inner side of the side piece a² of the frame. It passes through the brace A² and through the rear piece a⁴ of the frame and carries on its rear end a gear-wheel D². Said gear-wheel D² 50 meshes with a pinion E, that is mounted upon a shaft e parallel with the side a² of the frame, and said shaft has bearings in the brace A² and in the rear piece a⁴ of the frame and carries on its rear end the pitman-wheel E².

Said wheel E² has its crank-pin e² in engagement with one end of a connecting-rod F, the opposite end of which is hinged to one end of a slightly bent lever G, that is pivoted about the middle of its length, at g, to a bearing projecting from the inner face of the side 60 piece a of the frame. The opposite end of the lever G is hinged to one end of a connecting-rod H, that has its opposite end pivoted at h to the cutter k. Said cutter is guided, as usual, in its reciprocations by the 65 slotted fingers K, that are secured, as usual, to the under side of the cutter-bar a³. To the top and bottom of the rear piece a⁴ of the frame is secured the handle L, the front end of which is forked to allow for the passage of 70 the connecting-rod F. The rear piece a⁴ has also a slot along a portion of its length for the passage of the rear portion of the oscillating lever G.

On account of the location occupied by the 75 pitman and gears they are substantially protected from the grass falling in front of them, and they can easily be incased at little expense, if desired. The space between the sides of the frame is also substantially free 80 of obstructions that would otherwise receive the falling grass and prevent it from dropping directly upon the ground.

Having now fully described my invention, I claim—

In a lawn-mower the combination of a four-sided frame having all its sides in the same plane, and in one corner thereof an angular brace A² uniting two of said sides, two supporting-wheels on stud-axles, a beveled cog-wheel secured to the inner side of one of said wheels, a beveled pinion in engagement with said cog-wheel and having its shaft parallel with the supporting-wheels, and upon said pinion-shaft a gear-wheel in the rear 95 of the frame, a pinion E also in the rear of the frame, the bent lever G pivoted to one of the sides of the frame, and connecting-rods at each end of said lever, with the longitudinally-reciprocating knife substantially as 100 described.

In testimony whereof I affix my signature in presence of two witnesses.

EDWARD SCHREFFLER.
